TUBE ROLLING MILL

Fritz Kocks, Dusseldorf, Germany

Application August 5, 1933, Serial No. 683,868
In Germany February 10, 1933

9 Claims. (Cl. 80—13)

The present invention relates to rolling mills and more especially to mills for rolling thin-walled seamless tubes by stretching tubular blanks between inclined rolls.

It is an object of my invention to provide a rolling mill which is simple in design and economical in operation and which does not strain the metal in an unsatisfactory manner.

It is another object of this invention to provide a tube rolling mill which is particularly adapted for the production of seamless tubes of small diameters, for instance tubes about 50 to 100 millimetres in diameter, and the size and weight are only a small fraction of those of the rolling mills hitherto applied to the same operation, so that the first costs of a mill according to this invention will be far below the costs of such prior rolling mills.

The rolling mill according to this invention is fitted with inclined rolls, i. e., with rolls, the axes of which extend in different planes at an angle to one another, and more than two such rolls are provided in this mill in order to simultaneously act on more than two points of the circumference of the blank under operation.

Hollow blanks have already been transformed into tubes by stretching the blank in the axial direction between more than two inclined rolls. However, in these mills as hitherto designed the diameters of the rolls are very small in proportion to their length, i. e., the rolls are comparatively thin and, in view of this, require being supported by abutments on the side averted from the blank under operation.

In another type of rolling mills belonging to the same class the rolls are formed with annular projections or flanges designed to produce grooves in the blank in order to stretch same.

While the mills mentioned in the first place are complicated in design and costly in construction, the latter type of mills involves the drawback that the annular projections forming the main operative portions of the rolls are exposed to rapid wear and at the same time subject the metal of the blank to unsatisfactory stresses.

The tube rolling mill according to the present invention is also provided with more than two rolls arranged to cooperate in the rolling of the same circumferential area of the blank. However here the diameters of the rolls are large as compared with their length, so that the rolls are not exposed to any undue bending stress, and the rolls present a plain unbroken conical surface lacking all projections so that the lines delimiting the longitudinal section of the blank

under operation are not inclined to the axis of the blank more than 12° in any point.

In order to form a substantially enclosed pass and to thereby prevent the hollow blank from expanding in radial direction under the rolling strain, I may dispose filling pieces of a kind well known per se between adjoining rolls, the blank being thus enclosed in a circle of rolls and filling pieces alternating with each other and forming a virtually closed pass, in which the blank is forced to stretch axially without being allowed to give way to the rolling pressure in radial direction.

I have found the new rolling mill to be applicable to the rolling of seamless tubes and drums of any dimensions, but to be quite particularly useful in the manufacture of small tubes, for instance 50 to 100 millimetres in diameter. While the rolling mills hitherto in use for hot-rolling tubes of this kind were equipped with rolls, the diameter of which was the four- to six-fold of the diameter of the blank, I provide the mill with rolls having a diameter not exceeding one and one-half of the diameter of the blank, such as have hitherto been used only in connection with the rolling of materially larger tubes. I support these rolls in pairs of bearings, one at each end, these bearings being adapted to take up the entire rolling pressure. Since in rolls of this kind the axial length of the operative roll surface does not exceed twice the largest diameter, no inadmissible bending of the roll will arise and there is no need to provide abutments for the operative roll surface on the side averted from the blank. Since the operative roll surface is plain and devoid of all sharp-edged projections or flanges, the blank and the tube obtained from it are formed with a smooth surface free from projections and grooves.

In the practical operation of my invention I prefer using rolls, the largest diameters of which do not exceed 150 millimetres.

I have found it admissible and advantageous to operate a new rolling mill at the hitherto unheard of speed of at least 200 and preferably more than 400 revolutions per minute. By operating the mill at such high speeds a workpiece feed is obtained of 0.5 to 1 meter and even more per second, which, apart from the increase in output per unit of time, also insures uninterrupted operation and the possibility of producing tubes of far greater length and uniformity of wall-thickness than was hitherto possible with mills operating at lower speeds. For lower feeding velocity involves uneven cooling of the workpiece,

which tends to cause sticking of the tube between the rolls and consequent stopping of the mill.

The new rolling mill which, while being perfectly adapted for the manufacture of thin-walled tubes of small diameters by longitudinal stretching of the metal, is extremely simple in construction and its weight is only a small fraction, for instance about one tenth of the weight of a rolling mill with inclined rolls as hitherto used for the same purpose.

By providing a larger number of rolls I am enabled to form the rolls with an inclined rolling surface such that the blank can travel through the mill at a far higher speed than hitherto usual. Consequently the inclination of the direction of movement of the circumference of the rolls at the point of contact with the blank relative to the axis of the blank need not exceed 80°; that is, the tangent to the surface of the rolls in the direction of their rotation is inclined to the axis of the blank by an angle not substantially less than 80°.

I have found it useful to force, during the rolling operation, a lubricant into the gap between the mandrel and the blank in order to enable the rolls to displace and shape the metal with the least possible expenditure of power.

In order, further, to increase the efficiency of the mill by the creation of a high turning moment acting on the rolls, I have found it useful to increase the mechanical strength of couplings, coupling spindles, pinions etc. by hardening or tempering them, for I am thus enabled to transmit onto the rolls which may equally be hardened or tempered, twice or three times the turning moment hitherto possible.

In the drawing affixed to this specification and forming part thereof a rolling mill embodying my invention is illustrated diagrammatically by way 40 of example.

In the drawing

Fig. 1 is an axial section, with the rolls shown in elevation, while

Fig. 2 is a cross section on the line II-II in Fig. 1, and

Fig. 3 is a side elevation drawn to a smaller scale.

Referring to the drawing, 1 is the machine bed or housing and 2 are four inclined conical rolls, 3 being bearings supporting these rolls at either end. 4 are filling pieces, one between each pair of adjoining rolls, these pieces being mounted in the machine bed by means of keys 5 and embracing about one fourth of the circumference of each adjoining roll, their inner ends extending in close proximity of the tubular blank 6 mounted on a mandrel 7, which is formed with a central conduit 8 and a number of substantially radial branch conduits 9, through which lubricant is forced 60 from a reservoir 10 under the action of a piston 11. 12 are the couplings, 13 the coupling spindles and 14 is the motor driving the rolls by means of the pinions (not visible) mounted in the casing 15.

The conical faces of the rolls are shown to extend at an angle of not more than 12° to the axis of the blank and to be plain and devoid of all projecting parts or grooves, the axial length of the operative roll surface being less than twice the largest diameter. As shown more particularly 70 in Fig. 2, the rolls and the fillir pieces closely embrace the blank section under operation and the blank is thus prevented from giving way or being expanded radially under the action of the rolling pressure.

75 The couplings, coupling spindles and pinions

are hardened or tempered, and so are the rolls themselves.

The ratio of gearing between the driving motor and the rolls is so chosen that the rolls rotate at the rate of at least 200 and preferably 5 more than 400 revolutions per minute.

I wish it to be understood that I do not desire to be limited to the exact details of construction shown and described for obvious modifications will occur to a person skilled in the art. 10

I claim:—

1. In a mill for rolling preformed tubular blanks into thin walled seamless tubes not substantially exceeding 100 mm. in diameter, a stationary frame, fixed bearings mounted in said frame, and a mandrel, more than two high-speed rolls journaled in said bearings and arranged concentrically around said mandrel, and driving means adapted to drive said rolls at a speed not substantially less than about 400 20 R. P. M.; the said rolls having a diameter not substantially exceeding 150 mm. or 1.5 times the diameter of the blanks, the axial length of the operative surface of said rolls not substantially exceeding twice their largest diameter. 25

2. In a mill for rolling preformed tubular blanks into thin walled seamless tubes not substantially exceeding 100 mm. in diameter, a stationary frame, fixed bearings mounted in said frame, and a mandrel, more than two high-speed rolls journaled in said bearings and arranged concentrically around said mandrel, and driving means adapted to drive said rolls at a speed not substantially less than about 400 30 R. P. M.; the said rolls having a diameter not substantially exceeding 150 mm. or 1.5 times the diameter of the blanks, the axial length of the operative surface of said rolls not exceeding twice their largest diameter and being inclined with respect to the axis of said mandrel not 40 more than 12° at any point.

3. In a mill for rolling preformed tubular blanks into thin walled seamless tubes, a stationary frame, fixed bearings mounted in said frame and a mandrel, at least four inclined 45 high-speed rolls journaled in said bearings and arranged concentrically around said mandrel, and driving means adapted to drive said rolls at a speed not substantially less than about 400 R. P. M.; the largest diameter of said rolls not 50 substantially exceeding 150 mm. or 1.5 times the diameter of the blank, the axial length of the operative surface of rolls not exceeding twice their largest diameter and being inclined with respect to the axis of said mandrel not more 55 than 12° at any point, the tangent to the surface of said rolls in the direction of their rotation being inclined to the axis of the blank by an angle not substantially less than 80°.

4. In the rolling of tubular blanks into thin 60 walled seamless tubes having diameters not substantially exceeding 100 mm., the process which comprises rotating the rolls of a tube mill, provided with more than two high-speed rolls journaled in bearings fixed in a stationary frame and 65 arranged concentrically around a mandrel, at a speed not substantially less than about 400 R. P. M., feeding into said mill preformed blanks slideable along said mandrel at a rate not substantially less than about 0.5 meter per second 70 and stretching said blanks between said rolls into thin walled tubes; the said rolls having a diameter not substantially exceeding 150 mm. or 1.5 times the diameter of the blanks. 75

5. In the rolling of tubular blanks into thin

- walled seamless tubes having diameters not substantially exceeding 100 mm., the process which comprises rotating the rolls of a tube mill, provided with more than two high-speed rolls journaled in bearings fixed in a stationary frame and arranged concentrically around a mandrel, at a speed not substantially less than about 400 R. P. M., feeding into said mill preformed blanks 5 slideable along said mandrel at a rate not substantially less than about 0.5 meter per second 10 and stretching said blanks between said rolls into thin walled tubes; the said rolls having a diameter not substantially exceeding 150 mm. or 1.5 times the diameter of the blanks, the axial length of the operative surface of said 15 rolls not exceeding twice their largest diameter.
6. In the rolling of tubular blanks into thin walled seamless tubes having diameters not substantially exceeding 100 mm., the process which comprises rotating the rolls of a tube mill, provided with at least four high-speed rolls journaled in bearings fixed in a stationary frame and arranged concentrically around a mandrel, at a speed above 400 R. P. M., feeding into said 20 mill preformed blanks slideable along said mandrel at a rate not substantially less than about 0.5 meter per second and stretching said blanks, between said rolls into thin walled tubes, the largest diameter of said rolls not substantially 25 exceeding 150 mm. or 1.5 times the diameter 30
- of the blank, the axial length of the operative surface of rolls not exceeding twice their largest diameter and being inclined with respect to the axis of said mandrel not more than 12° at any point, the tangent to the surface of said rolls in the direction of their rotation being inclined to the axis of the blank by an angle not substantially less than 80°; said rolls being positioned to draw said blanks into tubing without other means of propelling said blanks through 10 said mill.
7. In a mill for rolling tubular blanks into thin-walled seamless tubes of small diameter, the combination of more than two skew rolls and guides arranged between said rolls, said rolls and 15 said guides forming a substantially continuous path around said tube.
8. In a mill for rolling tubular blanks into seamless tubes not substantially exceeding 100 mm. in diameter, the combination of more than 20 two skew rolls and guides arranged between said rolls, said rolls and said guides forming a substantially continuous path around the tubes.
9. In a mill for rolling tubular blanks into thin-walled seamless tubes of small diameter, 25 the combination of four skew rolls and guides arranged intermediate said rolls, said rolls and said guides forming a substantially continuous path around said tubes.
